DUPLICATING MACHINE

Paul A. Stephenson, Winnetka, Ill., assignor to
 A. B. Dick Company, Chicago, Ill., a corpora-
 tion of Illinois

Application March 19, 1937, Serial No. 131,766

4 Claims. (Cl. 271—53)

My invention relates to duplicating machines and the like and more particularly to sheet feeding devices for such machines, and it has for its principal object to effect certain improvements in apparatus of this character whereby the feeding of sheets into the printing couple of the machine may be effected more accurately and without slip or damage to the sheets, particularly at the higher speeds.

10 In duplicating machines as now commonly constructed, sheets are fed either manually or automatically from the feed board of the machine to a position in which the forward edge of the sheets is a short distance in front of the crotch, or line of contact between the elements of the printing couple. In this position each sheet is held until, the machine having cleared the preceding sheet, it is engaged by rotary feed segments which forward it into the crotch at a speed substantially equal to that of the printing cylinder. I 20 have found that the high velocity with which the feed segments engage the stationary sheet frequently causes the sheet to slip with respect to the face of the segments at the time of contact, causing a delay in the acceleration of the sheet to machine speed. This slip becomes more pronounced at higher machine speeds so as to adversely affect registration of the print. Moreover, the blow which is struck the back of the sheets 25 by the segments is frequently of sufficient force to permanently mark the sheet, particularly where soft or heavy papers are used, and such marking or nicking becomes much worse as the machine speed is increased, even to the extent of tearing the sheets.

30 One of the objects of my invention is to provide means whereby a sheet to be fed to the printing couple of the machine is picked up from rest by feeding members moving at a relatively low velocity, and is thereafter accelerated to the correct feeding speed, at or slightly above the speed of the machine.

Another object of the invention is to provide 40 means whereby the feed members are decelerated just before contact with a sheet to a desirably low velocity of contact, and are gradually accelerated after contact has been made to the desired feeding speed.

A further object of my invention is to provide 50 means for varying the speed of the feed segments through the previously mentioned cycle of deceleration and acceleration without noise or shock and without the imposition of undesirable stresses on the parts.

55 Other objects of the invention will appear from

the following description taken in connection with the drawings, which form a part of this specification, and in which:

Fig. 1 is a view in perspective of the delivery end of a duplicating machine, partially broken away to show the construction, illustrating the application of my invention;

Fig. 2 is a side elevation, partially broken away, of the velocity changing means of my invention;

Fig. 3 is a sectional view taken substantially on the line 3—3 of Fig. 2;

Fig. 4 is a sectional view taken substantially on the line 4—4 of Fig. 3, and

Fig. 5 is a sectional view taken on the line 5—5 of Fig. 3.

Referring to the drawings, at 10 is indicated generally a duplicating machine having the usual side frame members 11, between which are rotatably supported a printing cylinder 12 and an impression roller 13 which form the printing couple of the machine. The cylinder 12 is of well-known construction, being provided with a perforated diaphragm portion 14 through which ink may be fed from within the cylinder to a stencil 16 mounted on its outer surface. A driving pulley 17, rotatably mounted on one of the side frame members 11 co-axial with the cylinder 12 and operatively connected to the cylinder in driving relationship by any suitable means, is actuated through a belt 18 from a convenient source of power, not shown, which may be an electric motor. The other end of the cylinder 12 is supported by a bearing 19, formed in the hub 21 of a spur gear 22 which is rotatably mounted on the adjacent side frame. The gear 22 is connected to the cylinder 12 and is driven thereby, having for this purpose a notch 23 in its hub portion 21 adapted for engagement by a suitable dog on the cylinder, not shown.

The impression roller 13 is journaled at its ends in bearings 26, removably mounted in recesses or notches 27 in the ends of parallel arms 28, each of which arms is pivotally mounted as at 29 on one of the frame members 11. Tension springs 31, connected between the arms 28 and the frame 45 11 tend to swing these arms upwardly and urge the impression roller toward the cylinder 12 in the usual manner. The machine is provided with the usual feed plate 32, over which the sheets of impression paper, indicated at 33, are forwarded to the printing couple, and on which the sheets are brought to rest in feeding position by the usual stop-gate devices indicated at 34.

After being brought to rest in position on the plate 32, the sheet 33 being fed is picked up and

forwarded to the printing couple by suitable sheet feeding members, illustrated as rotary feed segments 36, which are operated in timed relation to the machine and which are provided with the usual arcuate paper engaging surfaces 37 adapted to contact the under side of the sheet. These segments 36 are fixed to and rotate with a shaft 38 which extends across the machine beneath the feed plate 32 and is journalled at its ends in suitable bearings on the frame members 11, not shown. The segments project upwardly through transversely spaced slots 39 in the feed plate, located between the stop-gates 34, so that the paper engaging surfaces 37 rotate slightly above the level of the plate 32. Cooperating with the segments 36 in the feeding of the sheets are feed rolls 41, adapted to engage the upper side of each sheet and to press it firmly into engagement with the segment faces 37. The rolls 41 are fixed to a shaft 42, which is journalled at its ends in levers 43, pivotally mounted as by hubs 44 on a rock shaft 46. The shaft 46 is journalled in suitable bearings, not shown, carried by the frame members 11, and is provided near its ends adjacent the levers 43 with fixed arms 47, having projecting lips 48 arranged to engage with abutments or flat portions 49 on the levers 43. These levers 43 are also provided with extension portions 51 to which are connected springs 52, urging the levers downward to resiliently press the rolls 41 against the sheet being fed. Suitable means is provided for oscillating the shaft 46 in timed relationship to the machine, so as to rock the levers 43 against the action of springs 52 and thereby raise the shaft 42 and rollers 41 out of contact with the plate 32, except when a sheet is to be fed. However, as such actuating and controlling means forms no part of the present invention, it has not been illustrated and further description is unnecessary.

The segment-driving and speed-controlling device of this invention, comprises means for continuously driving the segment shaft 38 from the machine, together with means for periodically decelerating and accelerating said shaft in a fixed cycle with respect to the printing cylinder. As best shown in Fig. 1, the driving means includes a train of gears operatively connecting the cylinder gear 22 to the shaft 38, including a pinion 55 meshing with and driven by the gear 22, a gear 56 meshing with and driven by the pinion 55, a gear 57 co-axial with the gear 56 and meshing with and driving a gear 58 fixed on the shaft 38, and a speed varying connection between gears 56 and 57. The constant speed gear 56 is rigidly secured as by a pin 59 to a shaft 61, journalled at its ends in bearings 62 formed in bosses 63 on the frame members 11, as shown in Fig. 3. It is formed with an elongated hub portion 64, forming a bearing on which is journalled the variable speed gear 57, co-axial with the gear 56 and spaced therefrom by a washer 66. The hub 64 also carries a locking ring 67, secured thereto as by a set screw 68, which engages the hub of the gear 57 and retains it in axial position.

The gears 56 and 57 are preferably of the same diameter and number of teeth, and are connected in power transmitting relation by the speed varying means of my invention. This means includes a lever 71, disposed between the gears 56 and 57 and pivotally connected to the gear 56 at its fulcrum as by a pin 72 mounted on the gear. The lever 71 carries a pin 73, which projects through an opening 74 formed in the gear 57

and is connected by a link 76 to a pin 77 secured to the body of gear 57. The lever 71 also carries a pin 78, which projects through an opening 79 formed in the gear 57 and is connected by a spring 81 to a pin 82, carried by the gear 56 and projecting through an opening 83 formed in the gear 57. 5

Thus it will be evident that gear 57 is driven by the gear 56 through the lever and link connection 71, 76 to rotate about the common axis 10 of the gears, and that any pivotal movement of the lever 71 about its fulcrum 72 during such rotation is imparted to the gear 57 through the link 76, to vary the angular relation of the gear 57 to the gear 56. If the gears are rotating together at a given velocity, movement of the lever 71 transmitted to gear 57 in the direction of rotation accelerates the gear 57; that is, increases its speed and advances it with respect to the gear 56. Conversely, movement transmitted to gear 57 from lever 71 against the direction of rotation decelerates the gear, reducing its speed and retarding it with respect to the gear 56. 15

To produce the movements of the lever 71 necessary to provide the periodic acceleration and 25 deceleration of the gears 57 and 58, shaft 38 and the feed segments 36, as contemplated by this invention, I provide a fixed cam 84, secured to the frame member 11 in any convenient manner, as by screws 86. Cooperating with the cam 84 30 is a cam follower 87 comprising a roller 88 mounted on a pin or stud 89 secured to the lever 71, projecting through an opening 91 in the gear 56. The roller 88 is held in operative contact with the cam 84, as the lever 71 is carried with gear 56 35 around the cam, by the tension of spring 81 which urges the lever 71 to turn in a radially inward direction about its pivot 72. A supplementary cam 92 is preferably provided for that portion of the cycle in which the pivotal movement of the lever 71, is most rapid, which occurs 40 just before the segments 36 make contact with the sheet to be fed. Thus during the pick-up period, the cam follower 87 is in contact with both cams 84 and 92 insuring positive movement of 45 the lever 71 without depending on the spring 81.

The operation of my device will be apparent from the foregoing description. As the leading edge of the segments 36 approach the sheet 33 to be advanced, the cam follower 87 moves on the 50 cam 84 from the high point, indicated on Fig. 5 at A, to the low point indicated at B. The corresponding movement of the lever 71 is transferred through the link 76 to the gear 57 being reduced as much as desired, for example one third. Deceleration of the gear 57 is transmitted through gear 58 to the shaft 38, so that at the point of contact with the sheets, the velocity of the segments 36 is relatively low. In this way the segments pick up the sheet and start it forward at 60 a reduced speed. After the sheet has been started, the follower 87 leaves the low portion of the same and rolls on the succeeding portion indicated at C, the profile of which may be a smooth curve of gradually increasing radius, as indicated. 65 As the roller 88 follows this part of the curve, the lever 71 and the link 76 are gradually moved in the direction of movement of the gear 57, resulting in a gradual acceleration of this gear and with it the gear 58, the shaft 38, and the segments 36. In this manner the sheet 33, picked up by the segments at a relatively low velocity, is thereafter accelerated to, or preferably slightly above the peripheral velocity of the cylinder 12 70 75

before its leading edge reaches and makes contact in the crotch of the printing couple.

By this means I am enabled to start the sheet from rest at a velocity sufficiently low to obviate slip when the sheet contacts the segments, and to accelerate it smoothly and uniformly to the desired feeding speed after contact with the segments has been established. It will be apparent that the absence of slip greatly improves the registration of the prints produced by the machine, and that the absence of shock at the moment of contact prevents damage to the sheets and reduces the noise of operation.

Having thus described my invention, what I claim and desire to secure by Letters Patent, is:

- 15 1. In a device adapted to feed sheets from rest, feed members to contact and advance each sheet, driving means for said members including a pair of coaxial adjacent gears, a lever pivotally mounted on one of the gears and disposed between said gears, a link pivotally connected between the lever and the other gear, and cam means actuating said lever to vary the angular relationship between the gears.
- 20 2. In a sheet feeding device, feed members to contact and advance the sheets, a driving gear rotating at constant velocity, a driven gear coaxial with and adjacent to the driving gear and operatively connected to actuate the feed members, lever means carried between and connected

to said gears to advance and retard the driven gear with respect to the driving gear, and a cam periodically actuating said lever means.

5 3. In a sheet feeding device, rotary feed members adapted to start a sheet from rest and to accelerate it to a pre-determined velocity, means to continuously drive said feed members including a constant speed gear and a coaxial variable speed gear, a lever member pivotally mounted on the constant speed gear between said gears, a 10 link pivotally connecting said lever member to the variable speed gear, a stationary cam, and a cam follower mounted on said lever member and operated by the cam to actuate said lever.

4. In a sheet feeding device to feed sheets from rest, feed members adapted to contact and advance each sheet, means to continuously drive said feed members including co-axially mounted driving and driven gears, a lever member pivotally mounted on the driving gear, link means 15 connecting the lever member to the driven gear, spring means connecting the lever member to the driving gear, a cam, and a cam follower mounted on the lever member and operated by the cam against the action of said spring means to vary 20 the velocity of the driven gear in accordance with the speed desired for the feed members throughout the cycle of the device.

PAUL A. STEPHENSON.
